P. SCHNEIDER ET AL

BLOCK TABLE PLANER

Filed Oct. 11, 1927

UNITED STATES PATENT OFFICE.

PETER SCHNEIDER, OF GLENDALE, AND JOSEPH KINSLER, OF NEW YORK, N. Y.

BLOCK-TABLE PLANER.

Application filed October 11, 1927. Serial No. 225,431.

This invention relates to a block table plane and has for one of its objects the provision of means for resurfacing a block table such as that used by tailors or of the 5 type used by butchers.

Another object of our invention is the provision of a block plane that can be conveniently transported and easily applied to tables of all sizes.

10 A further object of our invention is the provision of a plane of the class described comprising a rotary saw blade adapted to form a horizontal incision below the surface of a block table and a cutting member 15 mounted thereon adapted to cut or gauge away the material between the old surface of the table and the incision therein for providing a new surface.

A still further object of our invention is 20 the provision of a rotary saw blade adapted to cut into a table top on a horizontal plane below the upper surface of the table top and a rotary cutting member mounted on the saw blade and adapted to be rotated in the 25 opposite direction from the rotation of the latter for cutting away the layer of wood separated from said table top by the saw blade.

Other objects will appear hereinafter the 30 novel features and combinations being more clearly set forth in the appended claims.

In the drawings:

Fig. 1 is a perspective view of a planing device embodying our invention.

35 Fig. 2 is a top plan view of the planing device shown in Fig. 1.

Fig. 3 is a side view of our invention.

Fig. 4 is a sectional view taken on the line 4—4 of Fig. 3.

40 Fig. 5 is a sectional view of a modified form of our invention.

Fig. 6 is a central sectional view taken on the line 6—6 of Fig. 5.

45 Referring particularly to the drawings, the numeral 10 designates a block table top upon which my improved planing device is mounted. The body of the plane comprises a cast iron base portion 11 having a machined lower horizontal surface 12 which is adapted 50 to slide upon the old or used surface of the

table block. A motor 13 is mounted on the top portion 14 of the base 11 and is secured thereto by bolts 15. The shaft 16 of the motor is provided with a thrust bearing 17 and is rigidly attached to a bevel gear 18 disposed in advance of the base of the plane as shown in Figs. 2 and 3. A fan member 19 is secured to the shaft 16 for cooling the armature of the motor.

The front side of the base 11 is provided 60 with a handle 20 and the rear side 21 is provided with spaced brackets 22 and 23 and with a handle member 24. An extensible shaft comprising an upper section 25, a lower section 26 and an intermediate sleeve 27 is 65 journaled in apertures in the brackets 22 and 23. The upper section 25 is provided with a bevel gear 28 which is meshed with the bevel gear 18 of the motor shaft and the shaft section 25 is supported by a thrust bearing 29. The sleeve 27 is rigidly attached to the lower extremity of the upper shaft section 25 and is adapted to receive the upper end portion of the lower shaft section 26. There are a plurality of apertures in the 70 shaft section 26 adapted to register with apertures in the sleeve 27 for receiving a pin 30 by means of which the shaft section 26 may be secured to the sleeve 27 as desired. It should be understood that the shaft comprising sections 25 and 26 and sleeve 27 is 75 substantially vertical and that the same is adapted to be extended and made rigid by inserting the pin 30 in any registering apertures in the sleeve and section 26. It should also be understood that the shaft is rotated by the motor 13 through the bevel gears 18 and 28.

The lower extremity of the shaft section 26 is provided with a foot 31 which is rigidly secured thereto. A disc saw blade 32 is rigidly mounted on the bottom of the foot 31 by bolts, or the like, 33. A tool socket 34 is pivotally mounted on the foot 31 by a bolt 35 and is adapted to hold a cutting member 36. The socket 34 may be secured in a radial position or at an inclination to the radii of the foot 31 as desired and it is provided with a set screw 37 by means of which the cutting members 36 may be held in an extended or 100

retracted position. A guard member is mounted on the handle member 24 for protecting the hands of an operator from being injured by the saw blade 32 or the cutter 36.

5 In the operation of our device the plane may be manipulated by grasping the handles 20 and 24 and moving the entire device to the left as viewed in Fig. 3 while the motor 13 is driving the shaft and saw and cutting members. It should be understood that the shaft section 26 may be lowered suitably as above described for predetermining the thickness of the layer to be removed; it being understood that at all times when the device 10 is in operation the disc saw blade 32 extends below the machined surface 12 of the base 11, the amount to which the blade projects below the surface 12 depending upon the thickness 15 of the cut desired.

20 As the saw blade 32 is rotated it cuts its way into the block 10 and provides a smooth new surface. When a cut is taken which is deeper than the thickness of the saw 32 the cutter 36 serves to remove that portion of the 25 block material which extends above the saw blade 32 after the same has cut into the block. It should be understood that the saw blade teeth and the cutter 36 do not simultaneously work or cut on the same wood fiber. The saw 30 teeth sever the fibers first and the cutting tool follows up the saw blade. The distance between the place of cutting of the saw blade and that of the cutter 36 may be varied by extending or retracting the cutter 36 and re-setting the same with the set screw 37. The 35 angular position of the cutter 36 may be altered for adapting the device to the type of material it is to be cut.

40 In the modified form of our invention illustrated in Figs. 5 and 6, the foot 31' is provided with a toothed periphery which is adapted to mesh with the teeth of pinions 38 and 39. The pinion 38 is rotatively mounted on a rod 40 depending from the bracket 23 and the pinion 39 is rotatively mounted on a 45 rod 41 depending from the handle member 24. A ring 42 having cutting teeth 43 on its outer periphery and gear teeth 44 on its inner periphery is rotatively mounted on the saw blade 32 and the teeth of the pinions 38 and 50 39 are meshed with the gear teeth of the ring. The pinions 38 and 39 are provided with peripheral flanges which are adapted to engage over the upper surface of the ring 42 and the 55 foot 31' for holding the ring 42 from displacement. It should be understood that the cutting teeth 43 of the ring member 42 may be of any desired heights greater than the thickness of ring 42. When the foot 31' and 60 the disc saw blade attached thereto are rotated in a clockwise direction by the shaft and motor the ring member 42 is rotated by the pinions 38 and 39 in the opposite direction and thus, while the fiber of the table block is 65 being strained in one direction by the rotation

of the saw, that fiber immediately adjacent is being strained in an opposite direction by the cutting teeth of the ring member. This arrangement tends to prevent uneven breaking of the wood which would be apt to occur if the 70 strain caused by the cutting action of both members occurred in a single direction.

Obviously those skilled in the art may make various changes in the details and arrangement of parts of our invention without departing from the spirit and scope thereof. 75

Having thus fully described and shown an embodiment of our invention what is desired to be secured by Letters Patent of the United States is as follows:

80

1. A device of the class described comprising a base portion having a machined horizontal surface adapted to engage a table top, a motor mounted on said base member comprising a horizontal shaft, a vertical shaft 85 comprising an upper and lower section and a sleeve for joining the same rotatively mounted on said base member, bevel gears operatively connected to said motor shaft and said upper shaft section and meshed together, a foot member attached to said lower shaft sections, a disc saw blade mounted on said foot member, a tool socket adjustably mounted on said foot, and a cutting blade adjustably mounted in said socket adapted to cut away 90 wood fiber severed by said saw blade during rotation thereof.

95

2. A table plane of the class described comprising a disc member, teeth on the periphery thereof, a disc saw, a disc saw mounted on said disc member, a rotary cutting member mounted on said disc saw comprising a ring having gear teeth on its inner periphery, and pinions meshed with the gear teeth of said cutting members and the teeth of disc member for rotating said rotary cutting member in a direction opposite to the direction of rotation of said saw member for cutting away the material severed thereby.

100

3. A device of the class described comprising a standard, a vertical shaft journaled on said standard, a motor comprising a shaft operatively connected with said vertical shaft for rotating the same, a foot on the lower end of said vertical shaft, a disc saw blade rigidly attached to said foot comprising a toothed periphery, a ring rotatively mounted on said saw blade having cutting teeth formed on its outer periphery and gear teeth on its inner periphery and pinions rotatively mounted on rods extending from said standard, said pinions being meshed with the teeth of said foot element and the gear teeth of said ring for rotating the latter in a direction opposite to the direction of rotation of said saw member.

110

4. A table plane of the class described comprising a disc shaped attachment, a disc saw rigidly attached thereto, a socket member comprising a casing having a hollow outer 120

125

130

extremity and a flattened inner extremity disposed above said disc saw, a bolt extending through an aperture in said flattened extremity and a registering aperture in said attachment for adjustably securing said socket thereto, and a cutting tool adjustably secured in the hollow extremity of said socket,

said socket being adapted to adjustably hold said cutting tool at a desired inclination to the material being cut.

In testimony whereof we have affixed our signatures.

PETER SCHNEIDER.
JOSEPH KINSLER.
